UNITED STATES PATENT OFFICE.

EUCLID I. LA CHAPELLE, OF BROCKTON, MASSACHUSETTS.

SHOE-TURNING MACHINE.

1,336,750.

Specification of Letters Patent. Patented Apr. 13, 1920.

Application filed March 8, 1919. Serial No. 281,564.

To all whom it may concern:

Be it known that I, EUCLID I. LA CHAPELLE, a citizen of the United States, and resident of Brockton, in the county of Plymouth and Commonwealth of Massachusetts, have invented an Improvement in Shoe-Turning Machines, of which the following description, in connection with the accompanying drawings, is a specification, like 10 numerals on the drawings representing like parts.

My invention relates to an invention or improvement in machines for turning shoes of the type termed, turn shoes.

15 The object of my invention is to provide a machine that will enable the operator to manipulate the shoe in the machine during the shoe forepart turning operation, in a manner corresponding substantially to the 20 one employed when shoes are turned entirely by hand at the forepart, and, it is also the object of my invention to provide a compact machine, of simple construction, which may be easily operated and which may be 25 built at low cost and by which, both the heel part and the forepart of the shoe may be turned.

This invention relates more particularly 30 to shoe turning machines which are power actuated. Prior to my invention power actuated mechanisms have been produced for performing the operation of turning both, the heel part and the forepart of a shoe, but, so far as I am aware, such mechanisms 35 for turning the forepart of the shoe have not gone into practical use, particularly because of the liability of damage which is liable to be caused thereto. That is, in turning the forepart, great care must be 40 taken to prevent undue strain upon the upper and when the action is positive, as it is with power actuated machines, such undue strain is practically certain to be placed on the toe-end of the shoe in enough 45 instances to render the use of such machines impractical. Moreover, if the forepart turning mechanism has a stroke of definite length, and, as the shoes to be turned must necessarily vary in size, corresponding 50 adjustments are frequently necessary, or, if the length of the movement is dependent on a clutch mechanism, it has been found difficult to control the actuation with sufficient quickness to avoid frequent damage, one

of the chief difficulties being to prevent the 55 turning iron from being forced into the toe-end of the shoe too far, so as to punch out the toe-end to an extent sufficient to cause serious damage. As a matter of fact, unless this portion of the turning operation 60 is performed with extreme care, serious damage is likely to be caused.

Prior to my invention shoe turning machines, embodying heel part turning means and forepart means have been produced for 65 performing the operation of turning both, the heel part and the forepart of a shoe, but, so far as I am aware, no shoe turning machine has been produced in which the heel part turning means and the forepart 70 turning means have been combined and arranged, as in this present machine, whereby the heel part may be engaged and turned by a cup and thereafter may be disengaged therefrom preparatory to and during the 75 time that the forepart is being turned by its respective means, so as to permit the operator to manipulate the shoe in the machine in a manner similar to that practised by hand turners. This novel combination 80 of old elements brings about new, beneficial results never attained before. The heel turning cup, is a well known means in the art and is generally considered to be the best means adapted to that purpose and is 85 therefore employed in the machine shown herein.

Power actuated shoe turning machines have, so far as I am aware, and aside from the foot power actuated machines, been entirely clutch controlled, but I am not aware that a device of this character has been produced which may be practically employed for this purpose and which is continuously 90 actuated.

95 The objects of my invention are to produce a power actuated machine, embodying a heel turning cup, for turning shoes, in which the danger of injury being caused to the shoe forepart from the turning operation is practically eliminated by the shoe forepart turning operation being under constant and instant control of the operator, so that over-strain of the shoe, may be prevented at all times, without arresting the 100 movement of the machine, and, to provide a power actuated machine, embodying a heel turning cup, which may be continuously 105

actuated at a speed which will enable the operator to perform the turning operation on an indefinite number of shoes of different sizes, without stopping the machine. A further object is to provide a shoe turning machine, embodying a heel turning cup, in which the forepart turning operation may be partly performed by power actuated means and finished by hand in the machine. Another object is to provide a machine in which the heel turning cup and the forepart turning means are so combined and arranged that, the heel part and the forepart turning operations may be successively performed without changing the position of the shoe but slightly, thereby enabling the complete turning operation to be rapidly and satisfactorily performed. Still another object is to provide a machine in which the turning means, including a heel turning cup, are so combined and arranged that the shoe may be manipulated in a manner similar to that practised by hand turners.

It is a novel feature in shoe turning machines to combine and arrange a heel turning cup and a forepart turning means to accomplish the diverse objects enumerated and the appended claims are accordingly drawn to this novel feature.

I accomplish these objects in the manner hereinafter disclosed and by the means illustrated in the accompanying drawings in which:

Figures 1 and 2 are respectively side and front elevations of a shoe turning machine embodying my invention.

Figs. 3 to 6 are detailed views illustrating the different steps in the turning operation.

The complete machine, which is a preferred embodiment of my invention, is illustrated in Figs. 1 and 2 and comprises a base 10 having an upright support 12 mounted thereon and also a bearing 14 in which the main shaft 16 is journaled, said shaft having a driving pulley 18 on one end and a pinion 20 on the opposite end, the latter being arranged in mesh with a large gear 22, mounted on a shaft 24, also journaled in a bearing 50 on the base. The upright support 12 is provided with vertical guideways 26 in which a cross head 28 is mounted to slide, and a connecting rod or link 30 is pivoted to said cross head at one end and eccentrically connected to said gear 22 at the other end, so that as the gear is rotated said cross head will be reciprocated.

A round rod 32 (which I hereafter term a turning iron, as it corresponds in shape and function to the ordinary turning iron, or stick, generally employed in hand turning), is fixed on the upper end of the support 12, in a vertical position, said rod being provided with the usual friction roll 34 in its upper end, and a tubular cylindrical sleeve

or plunger 36 is slidably mounted on said rod 32 and is connected by a rod 38 to the cross head 28, so that said plunger will be caused to reciprocate on the rod 32 when the main shaft is driven. The upper end 70 portion of said plunger is tapered or beveled at its front side forming a beveled face 40 and is provided with a projection 42 at its rear side, the under side of said projection being corrugated, or provided with teeth. A bracket 44 is rigidly secured to the rear side of the support 12 and is extended upward and then downward in gooseneck form, the depending end thereof being provided with a heel part turning cup 46 of common 80 form, said cup being interchangeable to adapt the machine for shoes of different types, and is held in inverted position directly over the plunger 36, so that, when the latter is lifted, it will be passed into said cup 85 adjacent its walls.

The above described machine is primarily designed to be actuated continuously, at a suitable speed, and, when driven, the plunger 36 is reciprocated between the initial position, shown in Fig. 1, in which its lower end is in close proximity to the support 12 and its upper end is adjacent the middle portion of the rod, or iron 32, and a position in which its upper end is in close proximity 95 to the bottom of the cup 46.

The forepart turning means may be employed alone, minus the heel turning cup, and it is novel to provide forepart turning means, such as herein shown, with or without heel turning means, although I, preferably, employ a heel turning cup with the forepart turning means.

Under normal conditions and in the general run of a shoe factory, the operation is 105 as follows:

While the plunger 36 is being moved up, the operator places the heel portion of the shoe on the cup 46, with his left hand, within the shoe forepart, so that the rear part 110 edge of the latter engages the upper of the shoe close to the seam which connects the upper and the sole. The upper end of the plunger 36 is shaped to correspond to the interior surface of the cup, and as it moves 115 upward, engages the sole-seam of the shoe and forces it inward, or "breaks" it, as commonly termed, and, during the latter portion of its upward movement, it will engage the sole of the shoe within the points engaged by 120 the cup, as indicated in Fig. 3, whereby the continued upward movement of the plunger will cause the heel part of the shoe to be turned in the ordinary manner, as indicated in Fig. 4. The plunger then descends and 125 the operator presses the shoe downward and out of the cup with his right hand and slides it rearward on the upper end of the plunger and then bends it over the end of the projection 42 and presses it, at its shank 130

portion, preferably near the ball line, against the teeth thereof. Then, with his left hand still within the forepart of the shoe, he spreads the shoe upper and presses 5 the sole against the front side of the plunger and bends it longitudinally about the rounded front surface of the plunger, the shoe then assuming the position shown in Fig. 5. The plunger is, in the meantime, descending and by this time will have been moved down until its upper end is below the level of the roll 34, so that the sole will then be engaged by said roll. The sole is being held in engagement with the projection 42, 10 so that, as the plunger is moved down it draws down the sole over the roll 34. At the same time the forepart of the sole is held against the plunger, by the operator's hand within the forepart of the shoe, so that it 15 will be drawn over said roll, causing the forepart of the shoe to be turned. These manipulations of the shoe are substantially the same as when the forepart is turned by hand.

20 When the operator feels that the shoe is being unduly strained, or that the pull exerted thereon is excessive, he may instantly relax the force with which the sole is being held against the plunger projection 42 to release the shoe therefrom.

In some exceptional cases, as for example, with shoes that are made of very delicate upper material, to avoid the possibility of having the turning iron pressed against the 25 toe-end with sufficient force to cause injury to the upper, it is desirable for the operator to disengage the sole from the plunger before the toe part of the shoe is completely turned, and to finish the operation in the 30 machine on the turning iron, by hand. This may in fact be done at any time after the shoe is turned past the "tip-line", so called, up to which point it is usually of advantage to the operator to have the assistance of the 35 pulling action of the plunger. This hand operation may be finished during the latter portion of the downward movement of the plunger and during the first portion of the 40 upward movement thereof, so that the operator will have time to place the next shoe on the heel-turning cup before the plunger is raised into proximity thereto.

The power actuated turning means, whereby the forepart may be turned, is so arranged that the operation may be retarded, 45 for example, on shoes which require consecutive positioning of the sole upon the friction roll. When the operator feels that undue strain is being placed upon the shoe, 50 he may then release it from the turning means for an instant and thus retard the operation while he re-positions the sole of the shoe upon the friction roll toward either side of the sole, as may be necessary, and 55 thereafter he reengages the sole with the

plunger and the turning operation proceeds. The re-positioning of the sole upon the friction roll, during the time that the shoe forepart is partly turned, as herein explained, is often practised by hand turners, but no 70 machine, embodying a heel turning cup, had been produced, prior to my invention, so far as I am aware, which permits removal of the shoe from the heel turning cup and retarding of the shoe turning operation of the 75 forepart during the time in which that portion of the shoe is being turned, and, in the proximity of the toe-end, the retarding of the forepart turning operation may be advantageously practised upon many different 80 types of shoes.

It will be apparent that, while the machine herein described is especially designed and adapted for continuous actuation, it may be provided with a well known stop 85 mechanism, so that it will come to rest each time the plunger is moved to its lowest point. I do not, however, consider the incorporation of such means as either necessary or desirable, except in special cases, as 90 the speed of the machine can usually be gaged to correspond to the rapidity with which the workman is able to perform his work.

I want it well understood that I do not 95 limit myself to the use of power actuated means, although such is preferably employed.

What I claim as new and desire to secure by Letters Patent of the United States is: 100

1. A shoe turning machine, having, in combination, a heel turning cup, forepart turning means and actuating means for said forepart turning means, said forepart turning means being so arranged that the shoe 105 may be held in engagement therewith by the operator's hand directly upon the shoe during the time of its shoe turning actuation by said actuating means so that the progression of the shoe turning operation by said 110 forepart turning means may be constantly under the immediate control of the operator's hand.

2. A shoe turning machine, having, in combination, a heel turning cup, a forepart 115 turning iron, a sleeve mounted on said forepart turning iron and means for moving said sleeve in one direction to cause it to co-operate with said heel turning cup and turn the heel part and for then moving said 120 sleeve in the opposite direction to cause it to co-operate with said forepart turning iron and turn the forepart of the shoe.

3. A shoe turning machine, having, in combination, a heel turning cup, a forepart 125 turning iron, a slide and a sleeve connected to said slide and means for moving said slide in one direction to cause co-operation of said sleeve with said heel turning cup to turn the heel part and for then moving said 130

slide in the opposite direction to cause co-operation of said sleeve with said forepart turning iron to turn the forepart of the shoe.

- 5 4. A shoe turning machine, having, in combination, shoe turning means and power actuating means therefor, said shoe turning means being so arranged that the operator's

hand may be placed directly upon the shoe to control the duration of the shoe turning 10 operation by said shoe turning means under the influence of said power actuating means.

In testimony whereof I have signed my name to this specification.

EUCLID I. LA CHAPELLE.
